UNITED STATES PATENT OFFICE

OTTO R. HAAS, OF NORTH BEVERLY, MASSACHUSETTS, ASSIGNOR TO UNITED SHOE MACHINERY CORPORATION, OF PATERSON, NEW JERSEY, A CORPORATION OF NEW JERSEY

WINDING MACHINE

Application filed April 24, 1929. Serial No. 357,842.

The present invention relates to winding machines and more particularly to winding machines for winding sewing machine bobbins.

5 The bobbin winding machine herein disclosed as embodying the several features of the present invention is particularly adapted for producing filled bobbins having a portion of the thread wound on the bobbin in one direction and the remainder of the thread wound on the bobbin in the reverse direction and is similar in many respects to the machine disclosed in the patent to Topham, No. 1,625,232, dated April 19, 1927.

15 One object of the present invention is to provide in a machine of this general description a novel and improved mechanism for reversing the direction of the winding after a predetermined number of turns of thread 20 have been wound onto the bobbin.

A further object of the present invention is to provide a novel and improved means which will be simple in construction and efficient and reliable in operation for automatically rendering the winding mechanism inoperative after the mass of the wound material has reached a predetermined thickness.

Another object of the invention is to provide means for holding the thread in place 25 on the bobbin upon reversing the direction of the winding.

The several features of the invention consist in the devices, combinations, and arrangement of parts hereinafter described and 35 claimed, and together with the advantages to be obtained thereby, should be readily understood by one skilled in the art from the following description taken in connection with the accompanying drawings.

40 In the drawings, Fig. 1 is a view in front elevation of the bobbin winding machine herein disclosed as embodying in a preferred form the several features of the invention; Fig. 2 is a view similar to Fig. 1, partly in section, on the lines 2—2 of Fig. 5, illustrating particularly the driving mechanism for the winding shaft with the parts in rest position; Fig. 3 is a plan view of the machine as shown in Figs. 1 and 2; Fig. 4 is a detail 45 view of the connections for throwing the

timing mechanism into operation upon starting the machine in position directly after the machine has been thrown into operation; Fig. 5 is a view taken on the line 5—5 of Fig. 8; Fig. 6 is a left end elevation of the machine; 55 Fig. 7 is a sectional view in left elevation taken on the line 7—7 of Fig. 2; Fig. 8 is a view partly in section taken on the line 8—8 of Fig. 5 with the parts in rest position; Figs. 9, 10, and 11 are detail views of the overrunning clutch through which the timing mechanism is driven, Fig. 9 being a sectional view taken on the line 9—9 of Fig. 10, Fig. 10 being taken on the line 10—10 of Fig. 9, and Fig. 11 being taken on the line 11—11 of 60 Fig. 9; Fig. 12 is a view in right elevation taken on the line 12—12 of Fig. 1; Fig. 13 is a detail view of the thread contact finger; Fig. 14 is a detail view of the reversing clutch and its actuating cam; and Fig. 15 is a detail 65 view partly in section showing a modified construction of the bobbin spindle and adjacent portions of the winding shaft.

The bobbin winding machine herein disclosed as the preferred embodiment of the 75 present invention comprises a bobbin winding shaft which is driven from an electric motor through a reversing clutch which enables the shaft to be driven readily in either direction. The machine is thrown into operation, and is stopped automatically when a bobbin becomes fully wound, by means of a novel and improved starting and stopping mechanism which comprises an off and on switch for the electric motor, a thread contact lever connected to cooperate with the switch, and a toggle spring for controlling the operation of these parts. As the thread mass on which the thread contact lever rests reaches the required thickness, the toggle 80 spring is carried past its center position to throw the lever away from the bobbin and turn the switch to off position. The reversing clutch is controlled to cause the winding shaft to be driven in one direction during 85 the winding of the first part of the bobbin and thereafter in the opposite direction by means of a timing mechanism comprising a cam which is driven through one revolution upon starting the machine in timed relation 95 100

to the winding shaft and acts to shift the reversing clutch to drive the winding shaft first in one direction and then in the opposite direction during the continued operation of 5 the machine.

In order to insure proper handling of the thread upon reversing the direction of the winding, the construction herein illustrated also includes a pin which is inserted in the 10 bobbin upon reversing the direction of rotation to hold the thread securely in position and to serve as an anchor on the bobbin from which the thread is wound on the bobbin in the reverse direction. After a number of 15 turns have been placed on the bobbin, the pin is withdrawn and the winding is completed in the usual manner.

Referring more specifically to the drawings, the machine comprises a base 14 on 20 which is supported the electric motor 16 through which the machine is driven and a frame 18 within which is mounted the winding shaft 20. The winding shaft 20 is driven from the electric motor 16 through connections 25 comprising a shaft 22 which is journaled to rotate in the machine frame in alignment with the armature shaft 24 of the motor and is clutched thereto through the clutch members 26. At its free end the shaft 22 is provided with a pinion 28 which engages with a gear 30 which is formed on a sleeve 32 loosely mounted on the winding shaft 20. In order to permit the winding shaft 20 to be driven from the sleeve 32 in either direction, 35 a second sleeve 34 is loosely mounted on the shaft 20 and is continuously driven in an opposite direction through a chain of gearing which includes the bevel gear 36 formed on the sleeve 32, an intermediate idler gear 38 40 loosely mounted on a bearing pin 40, and a bevel gear 42 formed on the sleeve 34. A clutch sleeve 44 is keyed to slide on the winding shaft 20 and is provided at each end with clutch surfaces 46 which are adapted to engage 45 with the corresponding clutch surfaces 48 formed on the ends of the sleeves 32 and 34, so that the clutch sleeve 44 may be connected to either sleeve 32 or 34 to drive the shaft 20 in opposite directions.

50 The clutch sleeve 44 is moved into engagement with the sleeve 32 upon starting the machine to rotate the winding shaft 20 through a predetermined number of revolutions in one direction and is then moved into 55 engagement with the sleeve 34 to drive the winding shaft in the opposite direction during the continued operation of the machine by means of a yoke 50 sleeved on a shaft 52 and provided with rolls 54 which engage in 60 a groove 56 in the clutch sleeve 44. The yoke is also provided with a downwardly extending arm 58 adapted to engage with a cam 60 which is secured to a shaft 62 and forms a part of the timing mechanism hereinafter 65 to be described. A tension spring 64 secured

to one arm of the yoke 50, as shown in Figs. 5 and 8, holds the arm 58 at all times in engagement with the cam 60.

One end of the winding shaft is milled down to a reduced diameter as indicated at 70 66, to receive the bobbin 68 which is held clamped in position during the winding operation between a flange 70 rigidly secured to the winding shaft by means of a set screw 72 and a flange 74 which is screwed onto the 75 end of the reduced portion 66 of the winding shaft after the bobbin 68 has been placed on the spindle to clamp it securely in position.

The mechanism for throwing the machine into operation and for automatically stopping it when the bobbin 68 becomes fully wound comprises a feeler or lever arm 76 which is secured to one end of a rock shaft 78 and is provided with a roll 80 which is adapted to ride on the mass of the thread being wound on the bobbin. A lever arm 82 secured to the rock shaft 78 is connected by means of an adjustable link 84 to an arm 86 which is secured to a shaft 88 journaled in the machine frame at right angles to the shaft 78. The lever 76 with the cam roll 80 is held in contact with the mass of thread on the bobbin 68 until the bobbin is fully wound and then is moved out of contact with the bobbin by means of a toggle spring 90 which is secured 95 at one end to a pin 92 and at its other end to a pin 94 formed on an arm 96 on the shaft 88. As the mass of thread is built up and the lever 76 and cam roll 80 are moved outwardly, the shaft 88 will be rotated gradually to 100 a point where the spring 90 and the arm 96 pass center position, and thereupon the toggle spring 90 will act to rotate the shaft 88 quickly to the limit of its movement to cause the motor switch to be thrown out. The 105 feeler arm 76 is at the same time moved to its inoperative position out of contact with the bobbin as shown in Fig. 1. In order to determine exactly the amount of thread which is to be wound on the bobbin before 110 the toggle spring 90 is rendered operative to rotate the shaft 88 to a position corresponding to the off position of the motor switch, the pin 92 to which the toggle spring 90 is anchored is screw threaded for adjustment 115 in a bracket 97 on the machine frame. The point at which the lever arm 96 and the spring 90 pass center and act to throw the shaft 88 to open position can thus be altered to stop the machine after the desired thickness of thread has been wound on the bobbin. 120

The off and on switch for throwing the motor into and out of operation is indicated generally at 98 and is actuated by the feeler arm or lever 76 to turn the switch from on to off 125 position and back again through connections which comprise a shaft 100 journaled in the machine frame and secured at one end to turn with the switch. At its free end, this shaft 100 is provided with an arm 102 which 130

is adapted to cooperate with a corresponding arm 104 formed on the shaft 88 to control the movement of the switch. The rotary movement of the shaft 88 is transmitted to the shaft 100 to turn the switch from on to off position and back again by means of a small toggle spring 106 which is secured at one end to a pin 108 on the arm 102 and at its other end to a pin 110 on the corresponding arm 104 secured to the shaft 88. With the lever arm 104 on the shaft 88 raised as shown in Fig. 8 to correspond with the inoperative position of the feeler lever 76, the lever arm 102 is held in a raised position by the toggle spring 106 against the upper stop 111 so that the starting and stopping switch 98 controlled through the shaft 100 will be in an off position. When the feeler arm 76 is forced down into contact with the drum of a new bobbin by the operator to start the machine, the shaft 88 and lever arm 104 are rotated to swing the axis of the toggle spring 106 past center so that the lever arm 102 and shaft 100 will be rotated against the stop 113 as illustrated in Fig. 4 to close the starting and stopping switch of the motor. In order to secure a quick throw of the switch, the arms 102 and 104 are provided with corresponding flanges 112 and 114 which cooperate to prevent the movement of the shaft 100 and arm 102 under the pressure of the toggle spring 106 until after the spring has passed the center point by a considerable distance. When the lever 76 is forced down into contact with the bobbin to start the machine, it will be seen that the arm 102 is held against movement about its pivot by the contact of the flanges 112 and 114 until the flange 112 has entirely passed the end of the flange 114 at which time the toggle spring 106 will have passed the center point by a considerable margin. At this point the arm 102 will be moved rapidly about its pivot by the spring 106 to close the switch. As the lever 104 on the shaft 88 is gradually lifted with the feeler lever 76 during the winding of the bobbin, the lever 102 and shaft 100 are positively held in the operating position illustrated in Fig. 4 by the engagement of the flanges 112 and 114 until the shaft 88 and lever arm 104 are finally thrown to off position by the action of the toggle spring 90. The lever arm 102 and shaft 100 are then permitted to snap into the off position shown in Fig. 8 under the influence of the toggle spring 106.

In order to insure proper handling of the thread upon reversing the direction of the winding, mechanism is provided which acts to hold the thread in position upon the bobbin until after a number of turns have been wound on the bobbin in the reverse direction. This mechanism comprises a pin 116 which is secured to a sleeve 118 keyed to slide upon the winding shaft 20 and is adapted to extend through a perforation in the flange 70 and an

aperture or slot 117 formed in one of the flanges of the bobbin. When the direction of the winding is reversed, the pin 116 is moved across the drum or barrel of the bobbin 68 so that the thread is turned about the pin and is held securely in position both to prevent unwinding of the thread already on the bobbin and to form an anchor for the thread on the bobbin from which to start the new winding in the reverse direction. After a number of turns of thread have been wound on the bobbin in the reverse direction, the pin 116 is withdrawn and the winding is continued until the bobbin is fully wound.

The pin 116 is moved into operative position when the direction of winding is reversed and is then moved back again by means of a lever 120 which is pivoted at 122 on the machine frame and at its upper end is provided with a yoke carrying the rolls 124 to engage with a groove 126 formed in the sleeve 118 on which the pin 116 is supported. The lever 120 is connected by means of a link 128 to the upper end of a cam lever 130 which is loosely mounted on the pivot shaft 132 and carries a cam roll 134 adapted to engage in a cam groove 136 formed in the face of the cam disk 138 mounted on the shaft 62.

The timing mechanism for reversing the direction of the rotation of the winding shaft 20 and for moving the pin 116 into and out of operating position to hold the thread in position on the bobbin when the direction of the winding is reversed comprises the shaft 62 carrying the cams 60 and 138 and driving connections therefor including a one revolution clutch which is actuated upon starting the machine to rotate the shaft 62 and the cams 60 and 138 at a relatively slow speed through approximately one revolution in timed relation to the winding shaft 20. The driving connections for the shaft 62 comprise a gear 140 which is loosely sleeved on the shaft 62 and is continuously driven from the motor 16 through gearing which includes the gear 142 formed on the sleeve 34, the gear 144 meshing therewith secured to a rotary shaft 146 and the worm gear 148 which is also secured to the shaft 146 and meshes with the gear 140. The gear 140 is connected to drive the shaft 62 and the cams 60 and 138 by means of an overrunning clutch which is adapted to operate, when the machine is started, to rotate the cams through approximately one revolution. The component parts of the overrunning clutch (see Figs. 9, 10 and 11) comprise a sleeve 150 secured to the shaft 62 by means of a set screw 152. A second sleeve 154 is loosely fitted to the sleeve 150 and is provided with a series of slots in which cam rolls 156 are adapted to ride between the sleeve 150 and internal surface 158 formed in the gear 140. Flattened portions are provided on the sleeve 150 to permit the rolls 156 to rotate freely between the two surfaces for one

position of the sleeve 154. In order to bring the clutch members into locking engagement, a tension spring 160 is provided which is secured at one end to a pin 161 fastened to turn with the sleeve 150 and the shaft 62 and at its other end to a point in the sleeve 154, and acts to bring the rolls 156 into locking engagement with the corresponding surfaces of the sleeve 150 and the gear 140 to drive the shaft 62. The sleeve 154 is normally held against the pressure of the spring 160 to render the clutch inoperative to rotate the shaft 62 by means of a latch lever 162 which is loosely mounted on the pivot shaft 132 and is adapted to engage with a recess 166 in the sleeve 154. A tension spring 167 fastened to an arm of the latch lever 162 tends to hold it at all times in engagement with the periphery of the sleeve 154.

29 Mechanism is provided which acts automatically upon starting the machine to trip the latch lever 162 so that the shaft 62 carrying the operating cams will be permitted to rotate with the gear 140 through one revolution before the latch lever again engages with the recess 166 in the sleeve 154. This mechanism comprises a bell crank lever 168 which is loosely mounted on the shaft 132 adjacent to the latch lever 162 and is connected by a link 170 to the lever arm 102 for operating the off and on switch of the motor. In order to cause the latch lever 162 to be tripped when the lever arm 102 and the bell crank lever 168 actuated through the link 170 are thrown over in starting the machine, a small latch lever 172 is pivotally mounted at 174 on the free arm of the bell crank lever 168 and is held yielding in a position to cause one arm of this latch 172 to engage a corresponding abutment 176 on the hub of the latch lever 162 by means of a compression spring 178 which is held at one end in a recessed portion of the upwardly extending arm of the small latch lever 172 and at its other end in a corresponding recess in the bell crank lever 168. As the lever 102 of the starting and stopping switch and the bell crank lever 168 are moved from the rest position illustrated in Fig. 8 to the operating position illustrated in Fig. 4, the small latch lever 172 engages the abutment 176, thus causing the latch lever 162 to be moved against the pressure of its spring 167 to permit the shaft 62 to be operably connected to the driving gear 140 as previously described. The continued movement of the bell crank lever 168 about its pivot causes the outwardly extending end of the small latch lever 172 to come in contact with an adjustable stop screw 180 to disengage the latch from the abutment 176 as shown in Fig. 4 so that the latch lever 162 will be free at the end of one revolution of the shaft 62 and sleeve 154 to engage again in the recess 166 and stop further rotation of the shaft 62.

To secure a more accurate adjustment of the mechanism for rendering the one revolution clutch operative upon starting the machine, the link 170 is made in two parts which are rigidly connected by means of a nut 182 so that the length of the link 170 may be readily adjusted to vary the action of the bell crank lever 168.

An alternative construction for securing a bobbin on the winding shaft during the winding operation is illustrated in Fig. 15 on sheet 2 of the drawings. The end of the winding shaft 20 on which the bobbin is supported is ground to a smaller diameter as shown at 184 and a sleeve 186 is mounted thereon and held in fixed position by means of a pin 188. Spring arms 190 are formed on the inner end of the sleeve 186 and act to provide a frictional resistance to hold a bobbin in position on the winding shaft. In order to position the bobbin accurately on the winding shaft to bring the pin 116 into register with the corresponding aperture or slot in the flange of the bobbin and to hold the bobbin securely against rotation on the shaft, the pin 116 is adapted to slide in a bushing 192 which is mounted in the flange 70 and projects beyond the face of the flange into engagement with the aperture in the flange of the bobbin. As a safeguard against a possible slipping of the bobbin lengthwise on the winding shaft out of register with the bushing 192 during the winding operation, the bobbin is held in position by contact with the end of the feeler lever 76 which in this modification of the machine is made substantially the width of the bobbin to be wound as shown at 194 in Fig. 15. At the beginning of the winding operation, the end of the thread is threaded through the slot in the wall of the bobbin and is carried out between the bobbin and the flange 70 through a small slot 196 in the face of the flange 70 and is secured to a thread clamp 198 on the outer surface of the flange.

Briefly stated, the operation of the machine is as follows: In order to start the machine, the operator moves the feeler arm 76 down into contact with the drum of the bobbin so that the shaft 88 and the arm 104 of the snap switch are moved down into the position illustrated in Fig. 4, thus causing the off and on switch of the machine controlled through the toggle spring 106 and the lever arm 102 to be thrown into operative position to start the motor. At the same time, the one revolution clutch is rendered operative to rotate the shaft 62 carrying the cams 60 and 138 through one revolution to cause the winding shaft to be driven in one direction for a number of turns of thread on the bobbin and then to be driven in the opposite direction, and also to insert the pin 116 temporarily to hold the thread upon reversing the direction of the winding. The movement of the lever arm 130

102 of the off and on switch to operative position in starting the machine causes the link 170 to move the bell crank lever 168 from the position shown in Fig. 8 to that shown in Fig. 4, causing the small latch 172 to engage momentarily with the abutment 176 of the latch lever 162 to move the latch 162 out of engagement with the abutment 166 on the sleeve 154 of the one revolution clutch, the continued movement of the bell crank 168 causing one end of the small latch 172 to engage with the stop screw 180 to disengage the latch from the abutment 176 so that at the end of one revolution of the cam shaft 62, the latch lever 162 will again engage the abutment 166 to lock the shaft 62 against further movement. Starting from the rest position illustrated in Fig. 2, the rotation of the shaft 62 and the cam 60 in a clockwise direction will cause the cam lever 58 at once to ride off the high portion of the cam to disconnect the clutch sleeve 44 from engagement with the sleeve 34 and to engage the clutch sleeve 44 with the sleeve 32 to drive the winding shaft in a backward direction. After a predetermined number of revolutions of the winding shaft 20, the cam lever 58 will again ride onto the high portion of the cam to shift the clutch sleeve 44 into engagement with the driving sleeve 34 to reverse the direction of rotation of the winding shaft and drive it in a forward direction.

After a number of turns of thread have been wound onto the bobbin and just before the direction of rotation of the winding shaft is reversed as above described, the cam lever 130 is actuated by the engagement of the cam roll 134 in the cam groove 136 to advance the pin 116 across the barrel of the bobbin so that upon reversing the direction of the winding shaft, the thread is turned over the pin to anchor the thread at this point on the bobbin. After a number of turns of thread have been wound on the bobbin in the new direction, the pin 116 is again withdrawn by the action of the cam groove 136 on the cam lever 130. At the end of a complete revolution of the cam shaft 62, the latch lever 162 engages the abutment 166 to prevent further rotation of the shaft leaving the shaft and the cams 60 and 138 in the positions illustrated in Figs. 2 and 8, with the pin 116 in a retracted position and the cam lever 158 resting on the high part of the cam 60 to hold the sleeve gear 44 in engagement with the sleeve 34. As the bobbin becomes fully wound, the feeler arm 76 is gradually raised and the arm 96 is moved upwardly to a point where the toggle spring 90 passes center and acts to rotate the shaft 88 and the feeler arm 76 to inoperative position. At the same time, the lever 104 secured to the end of the shaft 88 is moved to its raised position shown in Fig. 8, and the lever 102 and shaft 100 of the off and on switch of the motor are permitted to snap into off position to stop the motor.

Having thus described the invention, what is claimed is:

1. A bobbin winding machine having, in combination, a winding shaft, driving connections therefor including an electric motor, an arm adapted to contact with the mass of thread on the bobbin, and a switch actuated from the arm to turn off the motor. 70

2. A bobbin winding machine having, in combination, a winding shaft, driving connections therefor including an electric motor, an arm adapted to contact with the mass of thread on the bobbin, and a switch actuated from the arm as the bobbin becomes fully wound to turn off the motor. 75

3. A bobbin winding machine having, in combination, a winding shaft, driving connections therefor including an electric motor, an arm adapted to contact with the mass of thread on the bobbin, and a stopping switch 80 for the motor controlled by the position of the arm. 85

4. A bobbin winding machine having, in combination, a winding shaft, driving connections therefor including an electric motor, an arm adapted to contact with the mass of thread on the bobbin, a starting and stopping switch for the motor controlled by the position of the arm, and a toggle spring to throw out the switch when the thread mass reaches 90 a predetermined thickness. 95

5. A bobbin winding machine having, in combination, a winding shaft, driving connections therefor including an electric motor, an arm adapted to contact with the mass of thread on the bobbin, an off and on switch for the motor, and connections including a toggle spring for actuating the switch from the arm. 100

6. A bobbin winding machine having, in combination, a winding shaft, driving connections for driving the shaft in reverse directions, mechanism for actuating and controlling the driving connections to drive the shaft in one direction during the winding of 105 a number of turns of thread on the bobbin and to drive the shaft in the opposite direction during the winding of the remainder of the thread on the bobbin, and a pin over which the thread is wound upon reversal of the direction of rotation of the shaft. 110

7. A bobbin winding machine having, in combination, a winding shaft, driving connections for driving the shaft in reverse directions, and a pin over which the thread is turned upon reversal of the direction of rotation of the spindle. 115

8. A bobbin winding machine having, in combination, a winding shaft, driving connections for driving the shaft in reverse directions, mechanism for actuating and controlling the driving connections to drive the shaft in one direction during the winding of 120 a number of turns of thread on the bobbin and to drive the shaft in the opposite direc- 125

tion during the winding of the remainder of the thread on the bobbin, a pin mounted on the shaft to rotate with the bobbin, and means for positioning the pin to cause the thread to be turned about the pin upon reversal of the direction of rotation of the shaft.

9. A bobbin winding machine having, in combination, a winding shaft, driving connections for driving the shaft in reverse directions, mechanism for actuating and controlling the driving connections to drive the shaft in one direction during the winding of a number of turns of thread on the bobbin and to drive the shaft in the opposite direction during the winding of the remainder of the thread on the bobbin, a pin, and connections from the said mechanism for positioning the pin in the bobbin upon reversal of the direction of rotation of the shaft to secure the thread with relation to the bobbin.

10. A bobbin winding machine having, in combination, a winding shaft, driving connections for driving the shaft in reverse directions, mechanism for actuating and controlling the driving connections to drive the shaft in one direction during the winding of a number of turns of thread on the bobbin and to drive the shaft in the opposite direction during the winding of the remainder of the thread on the bobbin, a pin mounted on the shaft to rotate with the bobbin, and means rendered active upon reversal of the direction of winding for positioning the pin to cause the thread to be turned about the pin as the direction of winding is reversed.

11. A bobbin winding machine having, in combination, a spindle on which the bobbin is supported, means for causing thread to be wound onto the bobbin while supported on the spindle, means for reversing the direction of the winding, and a pin about which the thread is turned when the direction of the winding is reversed.

12. A bobbin winding machine having, in combination, a spindle on which the bobbin is supported, winding mechanism for winding thread onto a bobbin while supported on the spindle, mechanism for actuating and controlling the winding mechanism to wind a number of turns of thread on the bobbin in one direction and thereafter to wind the bobbin in the opposite direction, and a pin about which the thread is turned upon reversing the direction of the winding.

13. A bobbin winding machine having, in combination, a winding shaft, driving connections for driving the shaft in reverse directions, mechanism for actuating and controlling the driving connections to drive the shaft in one direction during the winding of a number of turns of thread on the bobbin and to drive the shaft in the opposite direction during the winding of the remainder of the thread on the bobbin, a pin, and means for inserting the pin in the bobbin to hold the thread with relation to the bobbin upon reversal of the direction of winding.

14. A bobbin winding machine having, in combination, a winding shaft, driving connections for driving the shaft in reverse directions, mechanism for actuating and controlling the driving connections to drive the shaft in one direction during the winding of a number of turns of thread on the bobbin and to drive the shaft in the opposite direction during the winding of the remainder of the thread on the bobbin, a pin adapted to be inserted in the bobbin, and means for positioning the pin to cause the thread to be

turned about the pin upon reversal of the direction of rotation of the spindle, and thereafter for withdrawing the pin.

15. A bobbin winding machine having, in combination, a winding shaft, driving connections for driving the shaft in reverse directions, mechanism for actuating and controlling the driving connections to drive the shaft in one direction during the winding of a number of turns of thread on the bobbin and to drive the shaft in the opposite direction during the winding of the remainder of the thread on the bobbin, a pin, and connections from the said mechanism for positioning the pin in the bobbin upon reversal of the direction of rotation of the shaft to secure the thread with relation to the bobbin.

16. A bobbin winding machine having, in combination, a winding shaft, driving connections for driving the shaft in reverse directions, a cam actuated in timed relation to the winding shaft to maintain the driving connections in condition to drive the shaft in one direction for a number of revolutions of the shaft and thereafter to shift the driving connections to drive the shaft in a reverse direction, means for driving the cam including a clutch, and means for controlling the clutch to disconnect the cam during the continued rotation of the shaft.

17. A bobbin winding machine having, in combination, a winding shaft, driving connections for driving the shaft in reverse directions, a cam actuated in timed relation to the winding shaft to maintain the driving connections in condition to drive the shaft in one direction for a number of revolutions of the shaft and thereafter to shift the driving connections to drive the shaft in a reverse direction, means for driving the cam, and means for disconnecting the cam from its driving means after the shift in the connections for driving the winding shaft.

18. A bobbin winding machine having, in combination, a winding shaft, driving connections including a reversing clutch for driving the shaft in reverse directions, a cam driven from the driving connections in timed relation to the rotation of the shaft, and means controlled by the cam for actuating the reversing clutch after a number of revolutions of the shaft in one direction to drive the shaft in the opposite direction to fully wind the bobbin.

19. A bobbin winding machine having, in combination, a winding shaft, driving connections for driving the shaft in reverse directions, and a cam rendered operative upon starting the machine and driven through one revolution to maintain the driving connections in condition to drive the shaft in one direction for a number of revolutions of the shaft and thereafter to shift the driving connections to drive the shaft in a reverse direction.

19. A bobbin winding machine having, in combination, a winding shaft, driving connections for driving the shaft in reverse directions, a cam driven from the driving connections to maintain said connections in condition to drive the shaft in one direction for a number of revolutions of the shaft and thereafter to shift the driving connections to drive the shaft in a reverse direction, a one revolution clutch through which the cam is driven, and means rendered operative in starting the machine to throw the clutch into operation.

20. A bobbin winding machine having, in combination, a winding shaft, driving connections for driving the shaft in reverse directions, and a cam rendered operative upon starting the machine and driven through one revolution to set the driving connections to drive the shaft in one direction for a number of revolutions of the shaft and thereafter to shift the driving connections to drive the shaft in a reverse direction during the continued operation of the machine.

21. A bobbin winding machine having, in combination, a winding shaft, driving connections for driving the shaft in reverse directions, a cam driven from the driving connections in timed relation to the winding shaft, clutch connections through which the cam is driven rendered operative upon starting the machine to drive the cam through approximately one revolution, connections controlled by the cam to set the driving connections to drive the shaft in one direction for a number of revolutions of the shaft and thereafter to shift the driving connections to drive the shaft in a reverse direction, and a pin positioned by the cam upon reversal of the direction of rotation of the shaft to secure the thread with relation to the bobbin.

22. A bobbin winding machine having, in combination, a winding shaft, driving connections including a reversing clutch for driving the shaft in reverse directions, a cam driven from the driving connections in timed relation to the rotation of the shaft, means controlled by the cam for actuating the reversing clutch after a number of revolutions of the shaft in one direction to drive the shaft in the opposite direction, a pin, and connections controlled by the cam for positioning the pin with relation to the bobbin upon reversal of the direction of rotation of the shaft to secure the thread with relation to the bobbin.

23. A bobbin winding machine having, in combination, a winding shaft, driving connections therefor including an electric motor, an arm adapted to contact with the mass of thread on the bobbin, a switch and connections between the switch and the arm for actuating the switch to turn on the motor when the arm is moved into a position to

contact with the thread as it is wound on the bobbin.

24. A bobbin winding machine having, in combination, a winding shaft, driving connections therefor including an electric motor, an arm adapted to contact with the mass of thread on the bobbin, a switch and connections between the switch and the arm for actuating the switch to turn off the motor when the arm is moved in one direction by the thread mass, and to turn on the motor when the arm is moved in the opposite direction.

In testimony whereof I have signed my name to this specification.

OTTO R. HAAS.
